UNITED STATES PATENT OFFICE.

ANDREW E. WEST AND MARTHIN O. SAMPSON, OF MADISON, MINNESOTA.

HAY AND STRAW BURNER OR ATTACHMENT FOR STOVES.

SPECIFICATION forming part of Letters Patent No. 435,873, dated September 2, 1890.

Application filed May 8, 1890. Serial No. 351,062. (No model.)

To all whom it may concern:

Be it known that we, ANDREW E. WEST and MARTHIN O. SAMPSON, citizens of the United States of America, residing at Madison, in the 5 county of Lac-qui-parle and State of Minnesota, have invented certain new and useful Improvements in Hay and Straw Burners or Attachments for Stoves; and we do hereby declare the following to be a full, clear, and exact 10 description of the invention, such as will enable others skilled in the art to which it appertains to make and use the same, reference being had to the accompanying drawings, and to letters of reference marked thereon, which 15 form a part of this specification.

This invention relates to certain new and useful improvements in straw and hay burning attachments for heating and cooking stoves.

20 The object of the invention is to provide a casing which may be attached to the front of the stove and form a part thereof, or an independent attachment for stoves already manufactured; and it consists in a casing having 25 an opening which connects with the body portion of a stove, said casing having on one side a damper and at the opposite end a door or doors for the insertion and removal of fuel-containing receptacles, and a support for 30 holding the charged cylinders in an elevated position within said casing, the fuel-containing cylinders having openings for the admittance of air to the fuel and exit of the products of combustion, all as will be herein- 35 after fully set forth, and particularly pointed out in the claims.

In the accompanying drawings, Figure 1 is a perspective view of a hay or straw burning attachment, showing the same applied to a 40 cook-stove of ordinary construction. Fig. 2 is a transverse sectional view of the attachment separated from the stove. Fig. 3 is a perspective view of the fuel-containing cylinder.

45 A refers to a heating or cook stove of ordinary construction, to which our improved hay and straw burning attachment is applied, said attachment consisting of a shell or casing of sheet metal provided with suitable means for connecting the same, either permanently or detachably, to the stove in front 50 of the usual grate. This casing B has a

transverse opening b, through which the products of combustion pass into the grate-chamber of the stove, and opposite thereto a series of openings c, which are adapted to be 55 closed by a sliding damper d. At a suitable point the end sections of the casing are provided with inclined guide-strips e, which are held in place by rivets or bolts, and opposite these guides e are openings through which 60 the end portions f of a bail F extend, the outer bar f' of said bail being adapted to engage with a serrated bar g, so that the inner end f' 65 of the bail will be held in the proper position within the casing to maintain one of the fuel cylinders or chambers thereon in the upper portion of the casing B. The lower portion of this casing can have suitable supporting legs or feet, so that the opening b, through which pass the products of combustion, will 70 be located in the proper relative position to said stove.

The fuel-containing cylinders or chambers H are provided with longitudinal slots or openings h and i and with a central circumferential re-enforcing band i' and a permanently-attached head j. The end opposite the permanent-head j carries projecting pins k, with which engage slots on the flange of the removable head j', said head also having a central opening, through which can be passed a bent rod or poker for agitating or separating the contents of the fuel-chamber.

The cylinders are provided internally with a frame-work made up of several bands, to which 85 are attached longitudinal plates l and l', which are adapted to be turned within the cylinders, so as to be located over the openings h and i, to close the same when desired. One of these strips is provided with a projecting portion 90 or lug for operating or turning the plates. When the fuel-cylinder is properly supported within the casing, the smaller opening will be opposite the opening c, while the larger opening is opposite the opening b, through which 95 the products of combustion pass.

In operation the fuel chamber or cylinder, which has been packed with hay, straw, or other combustible material, is placed within the casing B and supported by the rod f' of 100 the bail F, and the fuel is ignited through the damper-opening c. After the contents of this

cylinder have been partially consumed the support F is drawn outwardly from the casing B and permits the cylinder to fall to the bottom of the casing, after which the bail can be slid again inwardly and a fresh cylinder placed in position. It will be observed that the heat and unconsumed contents of the first cylinder will pass upwardly and be utilized, and when the contents of the cylinder in the bottom of the casing have been entirely consumed said cylinder can be removed and repacked.

This device, as hereinbefore described, when in use throws a steady flame and can be recharged by inserting new cylinders without permitting the fire to go down, and it is cleanly, as the ashes can be removed from the cylinders, which can be taken from the stove and recharged. Therefore it is not necessary to lumber up the room within which the stove is placed with a quantity of light fuel as is intended to be used with our invention.

Having thus described our invention, we do not wish to be limited to the precise construction, but reserve the right to modify the same within the scope and spirit of our claims.

Having thus described our invention, we claim—

1. The combination, with a stove, of a casing B attached thereto or forming part thereof, said casing having an opening through which the products of combustion pass, and an air-inlet opening with a damper, a bail F, and a fuel-cylinder within the casing, said fuel-cylinder supported thereby and having openings for the admission of air and the egress of the products of combustion, substantially as set forth.

2. In a hay and straw or light-fuel burning attachment for stoves, a casing B, provided with openings for the exit of products of combustion and the entrance of air, inclined

guides or supports, a bar f^2 sliding therein, a catch for maintaining said bar in position, and a removable cylinder adapted to be sustained thereon, said cylinder having openings for the admission of air and egress of the products of combustion, substantially as set forth.

3. In combination with a shell or casing, means for securing the same to a stove, a fuel-containing cylinder and a support therefor so that said cylinder can be maintained in the upper part of the casing, the space below the said support for the cylinder being sufficient to contain a second cylinder, and doors at the end of the casing for the insertion and removal of the cylinders, substantially as set forth.

4. The combination, with the casing B and heating apparatus, of a cylinder within said casing and having longitudinal openings and an internal frame carrying longitudinal strips which are adapted to cover said openings, either in whole or in part, and a removable head secured to one end of the cylinder, said removable head having a central opening, the parts being combined and organized substantially as shown, and for the purpose set forth.

5. As an improved article of manufacture, a fuel-containing cylinder having longitudinal openings h and i , means contained in said cylinder for closing the openings, and a removable head having a slotted flange which engages with pins k on the ends of the cylinder, substantially as set forth.

In testimony whereof we affix our signatures in presence of two witnesses.

ANDREW E. WEST.
MARTHIN O. SAMPSON.
